UNITED STATES PATENT OFFICE.

MICHAEL J. MULVIHILL, OF WARREN COUNTY, AND JOHN DARE TINNEY,
OF VICKSBURG, MISSISSIPPI.

EARTH-EXCAVATOR AND EMBANKMENT-BUILDER.

SPECIFICATION forming part of Letters Patent No. 295,128, dated March 11, 1884.

Application filed October 12, 1883. (No model.)

To all whom it may concern:

Be it known that we, MICHAEL JOSEPH MULVIHILL and JOHN DARE TINNEY, residing, respectively, in the county of Warren and State of Mississippi, and at Vicksburg, in the county of Warren and State of Mississippi, have invented certain Improvements in Earth-Excavators and Embankment-Builders, of which the following is a specification.

10 In the drawings forming a part hereof, Figure I is a side elevation, partly in section, of the improved excavator. Fig. II is a plan of the same.

Similar letters of reference indicate similar 15 parts in both views.

A is the wheeled platform of the excavator, which is provided with a tongue or other means, (not shown in the drawings,) whereby it may be moved from one place to another.

20 B is the central post of the crane resting at its lower end in a step, a, and at its upper end supported by a frame-work, C, the cross-piece only of which is shown in the drawings.

D is the jib of the crane, and E the shovel-beam, to which the shovel F is attached. The under side of the shovel-beam E is provided 25 with a rack, b, which rests on a spur-gear, G, secured to the shaft c. The disengagement of the rack from the spur-gear G is prevented by

30 a plate, d, supported from the shaft c in any suitable manner, and the plate d has a roller, e, which bears against the upper side of the shovel-beam E. The reciprocating movement of the shovel-beam and shovel is effected as follows: A shaft, f, supported in bearings g, is fitted with a pulley, h, which is connected by a belt to an engine situated at any suitable place on the platform A. This shaft f communicates motion to a counter-shaft, i, through

35 the medium of the miter-gears k and k'. The shaft i, which is confined in bearings l, has a feather where it passes through the miter-gear k', to admit of its having a longitudinal movement independently of the said miter-gear.

40 H H' are friction-wheels secured to the shaft i, to give motion to a conical friction-drum, I, keyed to the shaft c. It will be understood that as the counter-shaft i has a longitudinal movement, either one of the friction-wheels H 45 H', which are fastened thereto, may be drawn

into contact with the friction-drum I. Consequently, the spur-gear, which is fastened to the shaft c, can be made to revolve in either direction, and the shovel to be forced out or drawn back by merely shifting the shaft i, as described. The means for shifting the shaft i are not shown in the drawings, as they may be of any approved construction and form no part of the present improvement. In order to allow of the longitudinal movement of the shovel-beam in the various positions in which the crane may be placed, we provide the conical drum I with a number of faces at such angles that when any one of them is made to touch the wheels H H' a proper contact is formed 55 with the whole face of the said wheels. We do not limit ourselves to any number of conical faces on the conical drum I, but provide as many as there are positions which the crane is designed to occupy.

50 By referring to Fig. I, it will be seen that the shovel F is hinged to the end of the shovel-beam m; consequently the outer end of the said beam and the shovel are required to be supported by different chains or ropes. The 55 possible angle of the shovel F with reference to the shovel-beam E may be limited to suit the degree of hardness of the earth to be excavated by means of an adjustable slotted stop-plate, n, which is bolted only to the upper side 60 of the shovel-beam, as shown in Figs. I and II. The wire ropes which support the shovel-beam and shovel are indicated by dotted lines denoted, respectively, by o and o', and by referring to Fig. II it will be seen that they lead to 65 hoisting-drums K and K'. The chains or ropes for moving the jib of the crane to the right or left are represented by p and p', and they are attached to other winding-drums, L and L', in the rear of the ones K K'. The drums K K' 70 and L L' receive their movement independently from a shaft, M, driven by means of a belt, q, from a pulley, q', on the shaft f. The shaft M, which is constantly in revolution, has two friction-wheels, N N', with which similar wheels, 75 O and O' and P and P', on the shafts or spin- 80 dles of the hoisting-drums K K' and L L', may be brought in contact. We do not show the levers and other devices which are employed 85 to move the hoisting-drums to bring their fric- 90

tion-wheels in contact with those on the shaft M, as it would tend to complicate the drawings, and they form no part of our invention.

The excavator is provided with a windlass, 5 (not shown in the drawings,) whereby it may be drawn from place to place.

From the foregoing description it will be seen that by properly manipulating the various shafts and hoisting-drums described, the 10 shovel may be moved in any manner necessary to produce its proper operation in excavating; consequently the description of the digging or excavating operation is unnecessary herein.

We claim as our invention—

15 1. In an excavator and embankment-builder, the shaft thereof, and mechanism connecting it directly to the shovel-beam, which shaft has a circumferential motion in common with the crane, and is provided with a friction-drum 20 having a series of frictional surfaces differing in angle of inclination, combined with a pair of friction-wheels on a shaft, and susceptible of movement to and from the surface of the said drum, and means to effect the said movement of the friction-wheels, substantially as 25 and for the purpose specified.

2. In an excavator and embankment-builder, a swinging jib, and a longitudinally-moving shovel-beam supported from the said jib, and adapted for elevation and depression, combined with a shovel hinged to the outer end of the said shovel-beam, and connected by an independent rope or chain to the said jib, whereby it may be emptied of its contents without affecting the position of the said beam, substantially as specified. 30 35

3. In an excavator and embankment-builder, a shovel-beam and shovel hinged together and supported independently by ropes or chains, combined with an adjustable stop secured 40 only to the said shovel-beam, and adapted to be projected and held at various distances beyond the end thereof, to limit the possible angle of the said shovel with reference to its beam when the former is elevated, substantially as specified. 45

M. J. MULVIHILL.
